UNITED STATES PATENT OFFICE.

WILLIAM H. HARRELSON, OF KANSAS CITY, MISSOURI.

AUTOMATIC CHAIR-MAT FOR CROSS-JETTY WORK.

SPECIFICATION forming part of Letters Patent No. 620,584, dated March 7, 1899.

Application filed May 24, 1898. Serial No. 681,554. (No model.)

To all whom it may concern:

Be it known that I, WILLIAM H. HARRELSON, of Kansas City, Jackson county, Missouri, have invented certain new and useful 5 Improvements in Automatic Chair-Mats for Cross-Jetty Work, of which the following is a specification.

My invention relates to automatic chair-mats for cross-jetty work; and my object is 10 to produce a device of this character which can be built and properly disposed in the stream at a comparatively small expense, which is of simple and durable construction, and which automatically accommodates itself 15 to the bed of the stream, and consequently prevents the water from cutting under the structure, and thus destroying its efficiency.

With this object in view the invention consists in certain novel and peculiar features of 20 construction and combinations of parts, as will be hereinafter described and claimed, and in order that it may be fully understood I will proceed to describe it with reference to the accompanying drawings, in which—

25 Figure 1 represents the chair-mat properly disposed with relation to the bed of the stream. Fig. 2 represents a perspective view of the chair-mat.

In practice it is desirable to build these 30 mats in sections of from twenty to fifty feet in length in order that the work of disposing them in the stream may be facilitated; but it is to be understood, of course, that I do not confine myself to any particular length or to any 35 number of mats employed in any particular piece of work, it being sufficient to explain that where a plurality of mats are employed they are to be fitted together endwise and preferably lashed to each other.

40 In the said drawings the seat portion of the mat consists of the parallel longitudinal logs 1 and 2 and the transverse or end logs 3, the latter preferably resting upon and lashed to the former by means of wire loops 4, said 45 loops being of the type illustrated and described in my Patent No. 554,777, granted February 18, 1896, on method of bracing and lashing riprap and jetty-work, reference to which is hereby made for a full understand- 50 ing of the same. In order to stiffen this

frame, I employ additional transverse logs or bars 5, which also rest at their opposite ends upon the longitudinal logs 1 and are lashed thereto by loops 4. The end logs or bars 3 are also connected at intervals of about a 55 foot, more or less, by the wires 6, which extend above the intermediate logs or bars 5, that the latter may relieve them of the greater part of the weight which the seat must sustain, and to give the rectangular frame rigidity I preferably employ the intersecting or obliquely-extending tie wires or rods 7, which are lashed or otherwise suitably secured at their ends to the corners of the frame by preference. The back of the chair-mat consists 60 of a plurality of upright logs or timbers 8, which are fitted in the crotches formed at the intersection-points of log 2 and the logs or bars 3 and 5 and the longitudinal log or timber 9, which connects the upper ends of the 7c uprights 8 and is secured to the same at the points of intersection by means of loops 4, and extending parallel with said log or timber 9 and preferably at intervals of a few 65 inches are wires 10, said wires being secured 75 in any suitable manner at their opposite ends to the end uprights 8. This back is secured reliably but pivotally to the log or timber 2 of the seat portion by means of loops 4, as shown, to the end that the seat portion 80 may operate pivotally when necessary to accommodate a deepening of the channel, and thereby prevent the stream from cutting under the seat portion, as will be presently explained, and in order to make the connection 85 between the seat and the back portion of the mat reliable the top log or timber 9 of the latter is connected to the former by the tie-rods 11, the latter consisting originally of loops connecting said parts and tensioned 90 to the requisite degree by the insertion of a bar or lever 12 through each loop in order to twist it at points intermediate of the logs 9 and 2 and of said twisting bar or lever, as shown at 13.

Preliminary to placing the chair-mats in position a row of piles 14 are erected at suitable distances apart along the line to be occupied by the chair-mats, and secured to the front side of the piling in a direction substan- 100

tially parallel with the bed of the stream are longitudinal connecting timbers or logs 15, these timbers or logs being secured to the pil-
 5 ing by means of loops 16, (like loops 4, if de-
 sired,) as shown, or in any other suitable man-
 nner, and to the top pole or timber 9 of the
 10 chair-back by means of loops 17 or equivalent
 means. The timbers 15 are so disposed that
 when the chair-mats are drawn out in the
 15 river and deposited at the proper points the
 top logs or timbers 9 of the chair-backs bear
 against the front side of the piling and the
 20 under side of the timbers 15. Consequently
 the tendency of the stream is to hold the
 25 chair-mat reliably in position. The log or
 timber 2 also bears against the piling along
 the bed of the stream, as shown in Fig. 1, and
 the seat portion rests upon the bed of the
 30 stream, as also shown in Fig. 1. Previous to
 placing these chair-mats in position it is pref-
 erable to weave branches or small limbs of
 trees, cornstalks, or other suitable material
 35 into the longitudinal wires of the seat portion,
 as illustrated in Fig. 2, and it may also be de-
 sirable to lash a bunch of branches or equiva-
 lent material to and below the front log or
 40 timber 1 of the seat portion, as shown in Fig.
 2, as these branches or cornstalks will more
 readily adapt themselves to the bed of the
 45 river than would the naked log or timber 1,
 and therefore more effectually and quickly
 prevent the water from cutting under the
 edge of the chair-mat. When the mat is
 50 properly disposed and secured to the piling,
 as described, sand-bags, rock, or equivalent
 material are dumped down on the seat por-
 tion, and owing to the skeleton or open-work
 55 construction of said seat portion it is impos-
 sible for the water to wash this ballast from
 position. The deposit of this ballast upon
 the seat portion forces the latter down upon
 60 the bed of the stream, and the water is com-
 pelled to find an outlet or passage between
 the wires 10 of the chair-back of this open
 construction in order that the water shall not
 65 be checked up too fast, because if this occurs
 it concentrates its pressure upon possibly a
 weak portion of the jetty and breaks through
 or else passes around and cuts another chan-
 70 nel at an undesirable point. By the con-
 struction shown it is checked sufficiently fast
 for all practical purposes without any possi-
 bility of the happening of the contingencies
 75 specified. The complete checking of the pas-
 sage of the water through the chair-back may
 be facilitated by placing suitable material—
 such as drift-wood, tree-branches, cornstalks,
 &c.—up against the front side of the chair-
 80 back and lashing it thereto, if desired. When
 the cross-jetty is completed, it is obvious that
 any tendency of the water to cut under the
 same is prevented, because the immense
 85 weight of the ballast, the gravitational tend-
 ency of the chair-seat, and the immense
 pressure of the water above force the chair-

seat pivotally downward as fast as the water
 cuts the sand from below it, as illustrated in
 Fig. 1.

If the stream to be cross-jettied is about six
 70 feet deep, I will preferably employ a chair-
 mat having a seat portion of about twenty
 feet in width more or less, and a back por-
 tion about eight feet in height, more or less.
 If this chair-mat was of rigid construction, it
 75 is obvious that the deepening of the stream
 would render the mat functionless; but it is
 obvious that the pivotal connection between
 the seat and back portions permits the for-
 80 mer to settle downward as the river gradu-
 ally cuts under until ultimately it may as-
 sume a position almost vertically pendent
 from the back portion, and consequently ac-
 85 commodate an increased depth in the river of
 nearly twenty feet, its usefulness, therefore,
 extending over a long period of service. 85

From the above description it will be appar-
 ent that I have produced an automatic chair-
 mat for cross-jetty work which embodies the
 features of advantage enumerated as desir-
 able in the statement of invention, and it is
 90 to be understood, of course, that I may resort
 to such changes as do not involve a departure
 from the spirit and scope of the invention.

Having thus described the invention, what
 I claim as new, and desire to secure by Letters
 95 Patent, is—

1. An automatic chair-mat, comprising a
 back portion, consisting of uprights connected
 at their upper ends to a longitudinal log or
 timber, and provided with a longitudinal se-
 100 ries of wires, and a seat portion comprising a
 skeleton rectangular frame, pivoted to the
 uprights of the back portion and provided
 with intermediate cross-bars, and with longi-
 105 tudinal wires resting upon said cross-bars and
 attached at their opposite ends to the end
 bars, substantially as described.

2. An automatic chair-mat, comprising a
 back portion, consisting of uprights connected
 at their upper ends to a longitudinal log or
 timber, and provided with a longitudinal se-
 110 ries of wires, and a seat portion comprising a
 skeleton rectangular frame, pivoted to the
 uprights of the back portion and provided
 with intermediate cross-bars, with longitu-
 115 dinal wires resting upon said cross-bars and
 attached at their opposite ends to the end
 bars, and with intersecting brace-wires which
 extend from corner to corner of said seat por-
 120 tion, substantially as described.

3. An automatic chair-mat, comprising a
 back portion having a top pole, and a seat por-
 tion pivotally connected to operate in a ver-
 125 tical plane to the back portion and including
 a back pole, and a twisted loop connecting
 the top pole of the chair-back with the back
 pole of the seat portion, substantially as de-
 scribed.

4. An automatic chair-mat, comprising a
 back portion, and a seat portion pivoted at 130

its rear edge to the back portion and adapted to swing in a vertical plane, in combination with piling against which the back pole of the seat portion and the top pole of the back portion bear, and longitudinal timbers connecting the poles at a suitable height and overlapping the top pole of the chair-backs, and loops connecting the top pole of the seat por-

tion with the longitudinal timbers of the pil-
ing, substantially as described.

In testimony whereof I affix my signature
in the presence of two witnesses.

WILLIAM H. HARRELSON.
